UNITED STATES PATENT OFFICE.

TONY DAVID, OF LYONS, FRANCE.

JACQUARD-CARD-PUNCHING DEVICE.

SPECIFICATION forming part of Letters Patent No. 631,395, dated August 22, 1899.

Application filed May 10, 1898. Serial No. 680,293. (No model.)

To all whom it may concern:

Be it known that I, TONY DAVID, a citizen of the Republic of France, residing at Lyons, France, have invented certain new and useful Improvements in Self-Acting Reading, (for which I have obtained Patent in France, deposited October 22, 1897, granted February 5, 1898, No. 271,548,) of which the following is a specification.

10 The features of the invention will be particularly described hereinafter and pointed out in the claims.

In the drawings, Figure 1 is a diagrammatic view showing, in the upper part, the needles and adjacent parts, while the lower portion of said figure shows the pattern-card, the switch, and the electrical connections. Fig. 15 2 illustrates the pattern, the comb and the circuit connections between the same, the 20 battery-switch, and the magnets.

The annexed drawings represent a pattern constructed A, in which the different zones are marked by $Z' Z^2 Z^3 Z^4$. We have supposed the zones being composed of unbroken surfaces in order to make the explanation easier. This pattern is fixed upon a wain B, running in a parallel direction to that of the warp, by means of a screw C, acted by a ratchet-wheel C', that makes the wain advance every time 25 30 for a quantity corresponding to a stroke of weft.

Upon the pattern A and in the direction of the weft a comb F is placed, of which the metallic teeth, thoroughly isolated among themselves, hold the place corresponding to the threads of warp.

The teeth of the comb F are respectively bound together by the conductors G to a set of electromagnets E E, acting, as further explained, on the needles of the jacquard J, which rules the punching of the cartoons. All the electromagnets E are from other part communicating by a similar conductor H with one of the poles of the pile P. The other pole of 40 45 the same pile is in communication with a commutator D, which one, by the means of contact-pieces $I' I^2 I^3 I^4$, sends forth at will the current to one of the zones $Z' Z^4$ of the pattern. This above so explained, it must be 50 55 understood the comb F by its occupying the place of any whatever stroke of weft and the commutator D being turned on the contact-

piece I' the current will only pass through the teeth of the comb lying on the zone Z' of the design, and through the corresponding electromagnets. Should the commutator D be turned on the contact I^2 , the current will only pass through the teeth of the comb lying on the zone Z^2 and through the corresponding electromagnets, and so on. Therefore it will be possible on every stroke of weft to put successively and separately at work the needles of the jacquard corresponding to the different colors or tyings-up composing the said stroke.

65 The jacquard J commands, by means already known, the punches of the machine punching the cartoons. The needles K of this jacquard could be acted by the electromagnets E; but in order to reduce the electric working we prefer to make use of an intermediate apparatus standing ahead of the jacquard and composed of a set of needles L, concording with the needles K and apart connected with an equal number of small and 70 very light pendulums M, the lower part of which serves as armature to the electromagnets E. When in rest, the pendulums M repose by a cranked part on the bars of a horizontal grate N, which receives at the requested time an ascending movement by 75 means of a cam O. Those of the pendulums M, which are drawn by their electromagnets, escape the grate and stay in place, as well as their needles L, while the others are rising up 80 and raise at the same time their own needles L. A vertical grate R, the voids of which are in front of the needles L at rest, pushes aside these ones among the said needles which have been raised, as well as the corresponding needles of the jacquard J. It results from such an arrangement that the electromagnets crossed by the current attract their pendulums M and lead them away from the power of the grate N. The corresponding 85 needles L and K are standing, and corresponding holes of the jacquard J are raised up by the claw S and determine corresponding holes are punched into the cartoon in work. The inactive electromagnets, on the contrary, leave 90 their pendulums M standing. These ones are raised up by the grate N, together with their needles, which then are pushed back by the grate R. The corresponding crooks of the 95 100

jacquard J escape therefore from the power of the grate S and not any hole is punched into the cartoon.

Every movement of the jacquard determines the punching of holes corresponding to the teeth of the comb F, which are at this moment in contact with the zone crossed by the current, and by working the commutator D it will be possible to punch separately and successively the holes corresponding to each one of the zones contained in the design.

At the present time the design is executed on a metallic surface with an insulating-varnish. All teeth of the comb which meet the metallic surface transmit the current to their corresponding electromagnets and actuate the corresponding punches for striking out the card. All parts of the design situated on the line of the comb are thus pierced on a single pattern-card. This method can serve only in the execution of a design of one color. Now the designs comprise in general different colors or different weft effects which cannot be produced by a single weft passage and which require as many pattern-cards as there are colors or different effects. My new card serves the purpose of successively punching these cards with the single design parts suited therefor. This is the whole invention. To that end the metallic parts of the card which correspond to each color or draft and tie are isolated from each other and make up that many zones connected to one switch or circuit-changer by which they can be introduced separately into the electrical circuit. When the comb comes into contact with the design, the teeth resting on the zone in the circuit alone transmit the current, and the punched pattern-card receives only the color or weft effects corresponding to that zone. Without disturbing the comb the record-zone then takes the place of the first one in the circuit and a new pattern-card is pierced in accordance with the effects of this second zone, and so on.

The transmission of movement of the electros to the needles of the jacquard, of the

needles to the punches, and of the mechanical movements actuating the machine are of common knowledge.

Referring to Fig. 2, A is the sheet of tin stuck on a non-conducting support. When the design is transferred in reverse on that sheet, the different colors are separated by small traces or furrows aa , in which the metal is taken out. Assuming three colors indicated by the letters Z^4 Z^2 Z^3 and shown by section-lines in different directions to distinguish them, as the color Z^2 is distributed over three insulated zones these three zones are connected under the card by a metallic wire and brought together at the key I' of the commutator. As the colors Z^4 and Z^3 make up only one zone each, they are connected, respectively, to the keys I⁴ and I³. The body of the comb F is of non-conducting material. Its metallic teeth are insulated from each other, and each is connected with one of the electromagnets E, which act upon the jacquard-needles. These electromagnets are, moreover, connected to one of the poles of the battery P, the other pole being connected with the switch D. Therefore the current passes only through the teeth which rest on the color corresponding with the key in contact with the switch D.

Having now described my invention, what I claim as new, and desire to secure by Letters Patent, is—

In combination, a card divided into metallic zones representing different colors insulated from each other and each zone representing wefts of the same color or nature, circuit connections and switch means to place the zones separately and successively into the electric circuit, substantially as described.

In witness whereof I have hereunto set my hand in presence of two witnesses.

TONY DAVID.
